UNITED STATES PATENT OFFICE.

VICTOR H. FAIRLESS, OF TRENTON, TENNESSEE.

SOFT-COLLAR SUPPORT.

1,378,773.

Specification of Letters Patent.

Patented May 17, 1921.

Application filed October 12, 1920. Serial No. 416,368.

To all whom it may concern:

Be it known that I, VICTOR H. FAIRLESS, a citizen of the United States, residing at Trenton, in the county of Gibson and State 5 of Tennessee, have invented certain new and useful Improvements in Soft-Collar Supports; and I do hereby declare the following to be a full, clear, and exact description of the invention, such as will enable others 10 skilled in the art to which it appertains to make and use the same.

The present invention relates to improvements in supports for soft collars and more particularly refers to an improved supporting device for holding soft or other collars in erect and proper positions in display cases and further for receiving and holding name and price tickets in association with the various collars on display.

20 Attempts to display soft collars in cases in the manner proposed with stiff collars usually proves very unsatisfactory because of the tendency of the collars to droop and fall out of shape which detracts from their 25 appearance. It is an object of the invention to provide an inexpensive, convenient and invisible means of supporting, in a natural position, a soft collar of any size or form in a standard display case.

30 Another object of the invention resides in providing an improved ticket holder for showing name and price of the collar which has become a very desirable feature because of the many varieties of collars and the large 35 range of prices.

Although the invention is more particularly adapted for use in connection with soft collars it will be understood that it may be employed to support starched collars, 40 especially for display in outside cases where the atmosphere soon causes the deterioration of the starch and the collar to gradually droop into an unnatural position.

With the foregoing and other objects in 45 view, the invention will be more fully described in connection with the accompanying drawings and will be more particularly pointed out in the appended claims.

In the drawings, in which like reference 50 symbols designate like or corresponding parts throughout the several views,

Figure 1 is a perspective of a collar with an improved support in position within the same.

55 Fig. 2 is a perspective view of the improved support removed from the collar.

Fig. 3 is a sectional view taken on the line 3—3 in Fig. 2, and

Fig. 4 is a sectional view taken on the line 4—4 also in Fig. 2.

Referring more particularly to the drawings, wherein one embodiment only of the invention is illustrated, 1 designates generally a soft or other collar of any particular style and size, it being a double collar having the inner and outer folds between which the necktie is customarily placed.

The front of the collar is provided with flaps 2 held together by the button 3.

In accordance with the invention a support is placed between the inner and outer folds of the collar 1 and near the upper end thereof where the folds meet in order to sustain the collar in an upright position and prevent it from drooping especially 75 under heavy atmospheric conditions. This support preferably takes the form of a thin round wire 4 of spring metal having one end 5 terminating near but short of the front opening of the collar. The intermediate 80 portion of the wire 4 which is located at the back of the collar is looped downwardly to provide a pair of parallel bars 6 and 7 engaged at their lower ends by a coupling piece 8 which is also fashioned from the 85 single strand of which the wire 4 is made and is a construction which results from the peculiarly looped form. The bars 6 and 7 receive the curled-over edges 9 and 10 of a plate 11 of tin or other suitable material 90 which is of a bendable character to allow of its edges being engaged with the bars in the manner best shown in Figs. 2 and 4. The upper ends of the plate 11 is bent down overlapping a portion of the plate as indicated at 12 and is provided to engage with standard fittings or clips to be found in display cases. The portion 12 of the plate 95 constitutes a flap which is bendable in either direction as may be required to fit the varying character of the clips.

The opposite end of the wire 4 is provided with a double looped construction in which an upper loop 13 bent at right angles from the general circle of the wire is adapted to engage with the upper edge of the rear flap 2 of the collar, it being concealed by the outer flap as indicated in Fig. 1. A second looped construction indicated at 14 extends downwardly from the first mentioned loop 13 and is arranged to receive the price and name tag or ticket 15 to the

collar as appears in Fig. 1. The extremity 16 of the wire at that portion is bent outwardly or is flared in order to form with the curved part 17 of the loop 13 a pair of divergent jaws to guide the ticket 15 into the loop. The flap 12 in combination with the plate 11 at the rear of the collar will receive the clips by which the collar is supported and will so sustain the collar that 10 all lateral movement will be prevented. The wire 4 will be so shaped as to give the proper contour to the collar and it will also be so arranged as to have a tendency to spring together at its free ends once the collar 15 has been buttoned and properly adjusted whereby the collar will be held in the desired close-fitting position rather than being stretched apart into a distorted shape. The loops 13 and 14 at the forward part of the 20 collar are carefully concealed by the flaps 2, the price ticket only being visible.

I desire it to be understood that various changes may be made in the size, form and proportion of the various parts provided 25 such changes are within the spirit of the invention and within the terms of the appended claims.

What is claimed is:

1. A collar support comprising a support- 30 ing member extending about within the folds of a collar at the upper closed portion of the same and having divided ends at the front portion of the collar, said support at one divided end provided with a clip re- 35 movable fitting over the top portion of the tabs of the collar, the intermediate portion

of the supporting member at the rear of the collar being formed into a pair of substantially parallel bars extending downwardly and being secured together by a coupling 40 piece at their lower ends, a plate connecting to said parallel bars and having a bendable portion adapted to engage with a support, substantially as described.

2. An improved collar support comprising 45 a spring wire having divided ends bent into substantially circular form and adapted to fit between the folds of a double collar at the upper closed portion of the same, the intermediate portion of the wire at the back 50 of the collar being offset downwardly to provide a pair of spaced apart and substantially parallel bars with a coupling piece 55 connecting the bars at their lower ends, a plate having edges curled about said parallel bars and provided with a bendable portion adapted to engage with a support, one of the free ends of the wire at the front 60 portion of the collar being bent at substantially right angles to the circle of the wire and extending inwardly thereof, said inwardly bent free end being formed into a clip with a mouth opening downwardly adapted to slip over the upper edges of the 65 tabs of the collar, said free end of the wire being further bent into a substantially U-shape to form a second clip lying inwardly of the first clip and having its mouth opening upwardly and concealed by the collar tabs, substantially as described.

VICTOR H. FAIRLESS.
